Primary Examiner — Elizabeth Albert(74) *Attorney, Agent, or Firm* — Calfee, Halter & Griswold LLP(57) **CLAIM**

I claim the ornamental design for a folder, as shown and described.

DESCRIPTION

FIG. 1 is a front/right/top perspective view of a first embodiment of the folder for which a front/left/top perspective view would be a mirror image thereof;
 FIG. 2 is a front elevational view for which a rear elevational view thereof would be identical;
 FIG. 3 is a top plan view thereof;
 FIG. 4 is a bottom plan view thereof;
 FIG. 5 is a right side elevational view thereof;
 FIG. 6 is a left side elevational view thereof; and
 FIG. 7 is a front elevational view thereof.
 FIG. 8 is a front/right/top perspective view of a second embodiment of the folder for which a front/left/top perspective view would be a mirror image thereof;
 FIG. 9 is a front elevational view for which a rear elevational view thereof would be identical;
 FIG. 10 is a top plan view thereof;
 FIG. 11 is a bottom plan view thereof;
 FIG. 12 is a right side elevational view thereof;
 FIG. 13 is a left side elevational view thereof; and,
 FIG. 14 is a front elevational view thereof.
